PAGE 2

FIG. 3.

-FIG. 4-

FIG. 1 is a top perspective view of a moulded plastic container for transporting live animals or birds embodying my new design;

FIG. 2 is a bottom perspective view thereof;

FIGURE 3 is a top perspective view of the bottom of the container of FIGURE 1, the lid having been removed for convenience of illustration; and

FIGURE 4 is an exploded perspective view thereof.

I claim:

The ornamental design for a moulded plastic container for transporting live animals or birds, as shown and described.
